UNITED STATES PATENT OFFICE.

GEORGE W. WALTERS, OF ELLIOTT, PENNSYLVANIA.

METALLIC MAT.

SPECIFICATION forming part of Letters Patent No. 728,525, dated May 19, 1903.

Application filed April 13, 1901. Serial No. 55,691. (No model.)

To all whom it may concern:

Be it known that I, GEORGE W. WALTERS, of Elliott, in the county of Allegheny and State of Pennsylvania, have invented a new and useful Metallic Mat, of which the following is a full, clear, and exact description, reference being had to the accompanying drawings, forming part of this specification, in which—

10 Figure 1 is a fragmentary top plan view showing a portion of my improved mat. Fig. 2 is a cross-section on the line II II of Fig. 1. Fig. 3 is a view similar to Fig. 1, showing a modified form. Fig. 4 is a view of a complete mat constructed in accordance with my invention.

My invention relates to that class of metallic mats wherein metallic strips are employed which are bent into zigzag or irregular shapes 2c and held so that the shoe contacts with the edges of the strips, and its object is to simplify, cheapen, and improve such mats and make them more resilient and elastic.

In the drawings, referring to the form of Figs. 1 and 2, I show a series of metal strips 2, each of which is bent into alternate V form. The strips are arranged so that the apices of the V-shaped bends meet or register, and these strips are held in position by wire helices 3, 30 which extend through the line of the junc- tures, while their coils embrace the abutting apices of the V-shaped bends. In order to provide for the reception of the coils at the points where they grip the strips, I preferably cut away the edge portions of the strips at such points, as shown at 4 in Fig. 2.

The end of the mat may be finished in any desirable manner; but I prefer to employ a two-ply strip 5, through which extend staples 40 6, which engage the apices of the end strip, the legs of the staple being bent in opposite directions within the two-ply finishing-strip. The edge portions of this strip may be doubled in and hemmed down to give a smooth finishing-strip, as shown in Fig. 2.

In Fig. 3 I show a form similar to that of Fig. 1, except that the adjacent apices of successive strips are arranged in alternate fashion and not abutting, as in the form of Fig. 1. In this form also the strips 2' are held together by spiral springs 3', the coils of which engage cut-away portions 4' at the apices of the alternate V-shaped bends.

The advantages of my invention result from the simplicity and cheapness of the mat, and, further, from its high resilience and elastic properties and its capability of being rolled up. It combines the valuable features of metallic-strip mats with those of wire mats, and presents a neat and attractive appearance.

The strips may be bent in many different shapes other than the V shape shown, and the arrangement and connection of the strips and spiral springs may be varied widely without departing from my invention.

I claim—

1. A metallic mat composed of strips of sheet metal bent into a series of figures, and wire helices extending between the strips and engaging cut-away portions of said strips; substantially as described.

2. A metallic mat containing a series of metallic strips bent into V-shaped figures, and wire helices extending between the strips and engaging cut-away portions at the apices of said figures; substantially as described.

3. A metallic mat comprising alternate strips of metal bent into zigzag shapes, and spiral springs engaging said strips, and a finishing-strip extending along the end of the mat and secured to the zigzag portions of one of the metal strips; substantially as described.

In testimony whereof I have hereunto set my hand.

G. W. WALTERS.
